(57) **CLAIM**

The ornamental design for a travel pillow, as shown and described.

DESCRIPTION

FIG. 1 is a bottom plan view of a Travel Pillow showing my new design;

FIG. 2 is a front elevational view thereof;

FIG. 3 is a left side elevational view thereof;

FIG. 4 is a rear perspective view thereof;

FIG. 5 is a front perspective view thereof;

FIG. 6 is a rear elevational view thereof;

FIG. 7 is a right side elevational view thereof;

FIG. 8 is a top plan view thereof;

FIG. 9 is a perspective view thereof showing a use state;

FIG. 10 is a perspective view thereof showing an unused state; and,

FIG. 11 is a left side view thereof showing an unused state; and,

FIG. 12 is a perspective view thereof showing an unfolding state.

The broken line showing of the chair and person is for the purpose of illustrating the environmental structure and forms no part of the claimed design.
